UNITED STATES PATENT OFFICE

CHESTER E. AGER, CARL KAIL, PHILIP KAIL, ALLAN AGER AND WILTON KAIL, OF LINCOLN, NEBRASKA

DESIGN FOR A REFRESHMENT STAND

Application filed July 8, 1929. Serial No. 31,973. Term of patent 14 years.

To all whom it may concern:

Be it known that we, CHESTER E. AGER, CARL KAIL, PHILIP KAIL, ALLAN AGER, and WILTON KAIL, citizens of the United States, residing at Lincoln, in the county of Lancaster and State of Nebraska, have invented a new, original, and ornamental Design for Refreshment Stands, of which the following is a specification, reference being had to the accompanying drawing, forming part thereof.

In the drawings,

Figure 2 is a view in side elevation of our refreshment stand, the figure being drawn to a scale which is somewhat less than that of Figure 1.

We claim:

The ornamental design for a refreshment stand, as shown.
